DIMMER CONTROL

Lawrence P. Mellyn, Gloucester, R.I., assignor to
General Electric Company

Filed July 2, 1970, Ser. No. 23,814

Term of patent 14 years

Int. Cl. D26—99; D13—03

U.S. Cl. D26—13

FIG. 1

FIG. 2

FIG. 3

FIG. 4

FIG. 5

FIG. 6

FIG. 7

FIG. 1 is a front perspective view of a dimmer control embodying my new design;

FIG. 2 is a side elevational view thereof;

FIG. 3 is a top plan view thereof;

FIG. 4 is a side elevational view thereof;

FIG. 5 is a back perspective view thereof;

FIG. 6 is a bottom plan view thereof;

FIG. 7 is a front elevation view thereof.

The textural surface shading is illustrated on portions of the front panel and rotary knob of the dimmer control and is understood to extend throughout the entire surface thereof.

I claim:

The ornamental design for a dimmer control, as shown and described.
